S. MACFERRAN.

Removable Head for Boxes.

No. 84,366.

Patented Nov. 24, 1868.

SAMUEL MACFERRAN, OF PHILADELPHIA, PENNSYLVANIA.

Letters Patent, No. 84,366, dated November 24, 1868.

IMPROVEMENT IN REMOVABLE HEADS FOR BOXES, &c.

The Schedule referred to in these Letters Patent and making part of the same.

To all whom it may concern:

Be it known that I, SAMUEL MACFERRAN, of the city and county of Philadelphia, and State of Pennsylvania, have invented a new and useful Improvement in Tightening-Straps for Paper and other Boxes; and I do hereby declare that the following is a full and exact description thereof, reference being had to the accompanying drawings, and to the letters of reference marked thereon.

The nature of my invention consists in the combination of an eccentric or wedge-bearing lever with a tightening-strap, for securing removable heads of round or elliptical paper boxes, wooden, metallic, or other ware, in their places.

The said lever is pivoted to the end of the encircling strap, and has on its inner side a permanent elliptical eccentric or curved wedge-shaped projection, which is placed in an elongated or elliptical slot in the other end of the strap, so that by turning the lever partly around, and bringing said projection to bear on the outer end of the slot, the inner periphery of the box or other vessel is brought tight against a rebate of the removable end, as hereinafter described.

In the accompanying drawings, which make a part of this specification—

Figure 1 is a top view of a paper box with the improved strap in connection therewith.

Figure 2 is a side elevation of the same.

Figure 3 is an edge view of a portion of the strap and lever in connection.

Figure 4 is a side view of the same.

Like letters in all the figures indicate the same parts.

A represents a paper box.

B is its lid, which has a rebate, a, that fits loosely in the end of the box.

C is an encircling metallic strap, which is secured to the outer periphery of the box by means of rivets b, each end of the strap being left free, so as to spring from or be drawn up tight against the box, to confine the lid E.

This is effected by the lever D, which has on its inner side a permanent elliptical projection, c, the pivot d, which connects the lever with the end of the strap C, being nearer the outer end of the projection.

To give the requisite thickness to the end of the strap, so as to properly support the pivot d, I connect the casting E therewith, by means of rivets e e.

On the other end of the strap there is a casting, F, similarly connected. This casting has an elliptical or elongated slot, f, in which the eccentric, c, of the lever D, is placed, and by turning the lever partly around, so as to bring the large side of the eccentric to bear on the outer end of the slot f, as seen in figs. 1 and 2, the strap is drawn tight against the rebate a; and when the lid is to be removed from the box, the latter is allowed to spring outwards, by turning the lever, so as to bring the eccentric, c, into the position shown in figs. 3 and 4.

The strap is made of such length that the position of the lever, shown in figs. 1 and 2, will give the maximum degree of tightening required. Sometimes it will not be required to turn it so far around.

I do not confine myself to making the tightening-projection c of elliptical form, as represented in the drawings, as a permanent or curved wedge, partly around the pivot d, will answer the purpose.

What I claim as my invention, and desire to secure by Letters Patent, is—

The combination of the lever D, having an elliptical or wedge-shaped projection, c, with one end of the tightening-strap C, and the slotted piece F with the other end of the strap, substantially in the manner above described and for the purpose specified.

In testimony that the above is my invention, I have hereunto set my hand and affixed my seal; this 27th day of May, 1868.

SAMUEL MACFERRAN. [L. S.]
